UNITED STATES PATENT OFFICE.

WILLIAM COX, OF TORONTO, ONTARIO, CANADA.

FARE-BOX-SUPPORTING STAND.

1,141,318.

Specification of Letters Patent. Patented June 1, 1915.

Application filed June 1, 1914. Serial No. 842,294.

To all whom it may concern:

Be it known that I, WILLIAM Cox, of the city of Toronto, in the county of York and Province of Ontario, Dominion of Canada, have invented certain new and useful Improvements in Fare - Box - Supporting Stands; and I hereby declare that the following is a full, clear, and exact description of the same.

10 My invention relates to a supporting stand for holding a portable fare box and shaking it so that the fares deposited in the examining chamber will, during such shaking movement, be delivered to the fare magazine.

15 For an understanding of my invention, reference is to be had to the following description and to the accompanying drawings, in which:

20 Figure 1, is a broken elevation of the fare box supporting stand, showing the parts in their normal position; Fig. 2, is a similar view of the supporting stand, looking at it from the opposite side to that shown in Fig. 25 1, showing the parts in their operated position; Fig. 3, is an end elevation of the fare box receptacle; Fig. 4, is a broken section on the line *a*—*a*, Fig. 3; and, Fig. 5, is a perspective view of the fare box receptacle.

30 Like characters of reference refer to like parts throughout the specification and drawings.

The fare box receptacle *a* is connected to the standard *b*, by a hinge *c*, so that it 35 can move between the positions shown in Figs. 1 and 2. Projecting downwardly from the fare box receptacle *a* is a lug *d* to which is pivoted the upper end of a bent connecting rod *e*, movable through the guide 40 *f*, fixed to the standard *b* below the hinge *c*. On the connecting rod *e*, above the guide *f*, is a collar *g*, and on the connecting rod between the collar *g* and the guide *f* is a spring *h*. Pivoted to the lower end of the 45 connecting rod *e* is one end of a link *i*, the opposite end of the link *i* being pivoted to the treadle *j* by which the connecting rod *e* is drawn downward to turn the fare box receptacle, with the fare box *k*, from the 50 position shown in Fig. 1 to that shown in Fig. 2, the spring *h* when the pressure is removed from the treadle *j* restoring the connecting rod with the receptacle and fare box to the position shown in Fig. 1.

55 For the collection of the fares, the fare box is placed in the receptacle *a* so that the

fares can be deposited therein; the fare box and receptacle during such deposit of the fares occupying the position shown in Fig. 1. When the fares have been deposited in 60 the fare box the person in charge of the apparatus, by pressing on the treadle, can rock the receptacle and fare box from the position shown in Fig. 1 to that shown in Fig. 2 and by repeating this pressing movement 65 two or three times can impart a sufficient jarring movement to the fare box to cause the fares to move from the examining chamber into the fare magazine of the fare box. To prevent the endwise movement of the 70 fare box during such jarring movement, a packing member *l* is placed within one side *a'* of the receptacle and this packing member is provided with a bent part *l'* terminating in a downturned arm *l''* secured at its 75 lower end to the outer face of the same side of the receptacle. Between the arm *l''* and the outer face of the side *a'* of the receptacle, is a spring *m* which presses the arm *l''* outwardly and normally holds the packing 80 member *l* in contact with the inner face of said side *a'*. On the bent part *l'* is a curved buffer *o* engaged by a semi-circular plate *p* secured to the end of a hinged member *q*. The member *q* is hinged at *r* to the side *a''* 85 of the receptacle *a* and this member is provided with a strap *s* which passes through the handle *t* of the fare box and is secured to the receptacle by a hasp *u*, the purpose of the strap *s* and hasp *u* being to fasten the 90 fare box in the receptacle.

Projecting from the standard *b* is a finger *b'* which extends partly across the outer face of the hinged member *q* when the receptacle is in the position shown in Fig. 1, to prevent the hinged member then being opened for the removal of the fare box *k* from the receptacle. When the receptacle is in the position shown in Fig. 2, the hinged member *q* is clear of the finger *b'*, and it can 95 then be opened for the removal of the fare box, the purpose of this being to compel the user to move the fare box to the position shown in Fig. 2, so that the fares in the examining chamber will be delivered into the 100 fare magazine, prior to the removal of the fare box from the receptacle.

When the fare box is in the receptacle it can be used as a stationary fare box and when removed therefrom it can be used as a 110 portable fare box.

Having thus fully described the nature

of my invention, what I claim as new and desire to secure by Letters Patent, is:

1. In a fare box supporting stand, the combination of a support, a fare box receptacle hinged thereto, a spring tensioned rod connected to the receptacle, a guide for the connecting rod, and a treadle connected to said rod.
- 10 2. In a fare box supporting stand, the combination of a support, a fare box receptacle hinged thereto, a spring tensioned rod connected to the receptacle, a guide for the connecting rod, a treadle, and a link connecting the treadle to the connecting rod.
- 15 3. In a fare box supporting stand, the combination of a support, a fare box receptacle, a spring tensioned packing member on the inner side of the fare box receptacle, a member hinged to the outer side 20 of the fare box receptacle, and a plate car-

ried by said hinged member to press the packing member against the fare box in the receptacle.

4. In a fare box supporting stand, the combination of a support, a fare box receptacle, a spring tensioned packing member on the inner side of the fare box receptacle, a hinged member on the outer side of the fare box receptacle, a plate carried by said hinged member to press the packing member against the fare box in the receptacle, and means carried by said hinged member to lock the fare box in the receptacle.

Toronto, May 20th, 1914.

WILLIAM COX.
